UNITED STATES PATENT OFFICE.

RAYMOND C. BENNER, OF BAYSIDE, AND HARRY F. FRENCH, OF FLUSHING, NEW YORK, ASSIGNEES TO NATIONAL CARBON COMPANY, INC., A CORPORATION OF NEW YORK.

DRY CELL AND PROCESS OF MAKING THE SAME.

Application filed June 27, 1922. Serial No. 571,176.

To all whom it may concern:

- Be it known that we, RAYMOND C. BENNER and HARRY F. FRENCH, citizens of the United States, residing at Bayside and Flushing, in the county of Queens and State of New York, have invented certain new and useful Improvements in Dry Cells and Processes of Making the Same, of which the following is a specification.
- 10 This invention relates to improvements in the lining of metal container electrodes, particularly the zinc cup forming the anode of dry cells. In its preferred form, the invention comprises a layer of toughened 15 real paste uniformly adherent to the inner surface of the container, and a sheet of bibulous fibrous material contiguous to the paste layer.
- In our Patents 1,295,475, dated Feb. 25, 20 1919, and 1,375,202, dated April 19, 1921, we have described and claimed methods of forming a lining of toughened paste in metal cups, the particular object in view being to facilitate the manufacture of cells of the 25 type in which a molded, coherent body of depolarizer, or mix bobbin, is used. With cups so lined, particles of the depolarizing composition which may separate from the bobbin can not come into contact with the 30 metal, and it is therefore unnecessary to supply the bobbin with the fabric wrapping or other disintegration-preventing means which would otherwise be required.
- In some cases, however, it is desirable to 35 use a plurality of linings between the zinc and the mix, for example a layer of toughened paste and a sheet of bibulous fibrous material, such as pulpboard.
- The applications and advantages of the 40 plural lining construction will be described in detail hereinafter, reference being had to the accompanying drawing, in which the figure is a vertical longitudinal section through a dry cell having a double lining.
- 45 Referring to the drawing, reference numeral 1 denotes a metal container electrode, which will usually be a zinc cup, and 2 a layer of toughened cereal paste therein. The method of forming this layer is not 50 a part of the present invention. It may be formed according to the processes described in our patents above referred to, in which the paste is gelatinized by heat, or according to the chemical gelatinizing method disclosed in the application of Benner and Mac-
- Kenzie, Serial No. 547,226 filed March 27, 1922, or by any other method resulting in a thin, tough layer of substantially uniform thickness throughout. A preformed sheet of bibulous material 3, preferably pulpboard, is bent to conform to the shape of the container 1 and placed in contact with the paste layer. A disc 4 of bibulous material is fitted in the bottom of the container. 60 5 indicates a carbon rod surrounded by a conductive depolarizing composition 6, which is preferably tamped into the container about the rod. A seal 7 closes the cell.
- The sheet of bibulous material 3 and the 65 paste layer 2 will usually be supplied with the proper amount of water before tamping, unless the cells are of the deferred action type. In this case, liquid will not be added until it is desired to activate the cell.
- A particular advantage of the double lined construction, as shown in a preferred form in the drawing, resides in its capacity to absorb and retain moisture. In cells with 70 tamped mix, as heretofore manufactured, a lining of bibulous paper or the like has been used to space the mix from the zinc. The lining may be associated with paste or paste-forming materials, but no paste layer having any considerable absorptive capacity for 75 water has heretofore been used in connection with the lining in such cells. The mix of course contains moisture, but its moisture content is very much lower than that of cereal paste or wet bibulous paper. To the 80 low moisture content of cells with tamped mix is to be ascribed their usual inability to give service equivalent to that obtainable from cells of the "bag type", that is, cells in which the bobbin is encased in a wrapping of textile fabric or paper and surrounded by a relatively thick layer of paste 85 of high water content.
- According to this invention, the components of the double lining cooperate in the 90 formation of a cell having a moisture content substantially equal to that of bag type cells, while obviating the necessity for resorting to the tedious and expensive bobbin wrapping or protecting processes. The paste 95 layer adherent to the zinc may be made of sufficient thickness to take up and hold the desired amount of moisture, and the protection afforded by the sheet of pulpboard or the like makes it possible to tamp the de- 100 105 110

polarizing mix into the cell without piercing the paste layer. Further, the corrosion of the zinc is more uniform when the paste layer is used in connection with the bibulous lining sheet, as such layer provides a smooth, continuous surface in close engagement with the metal, insuring a more even distribution of the electrolyte than is obtainable when the bibulous fibrous sheet alone is used. Cells with the double lining described may be economically manufactured and operate efficiently during a long service life.

Among other advantages of the double lining may be mentioned the increased protection against access of mix particles to the zinc, and the resulting freedom from corrosion due to local action set up about such particles in contact with the metal. Also, arborescent metal deposits which are sometimes of sufficient extent to connect the mix and zinc through a single fibrous lining will rarely pierce both the paste layer and pulpboard sheet.

While particular reference has been made to cells with tamped mix, the invention is not limited to cells of this type. Molded bodies of depolarizer, either with or without a wrapping of fabric or other surface protection, may be used in connection with the double lining described herein. The lining sheets will usually be formed from a fibrous material such as pulpboard or cloth, which may carry paste or paste-forming materials, but thin walled cylinders of wood, or other suitable absorptive substance, may be used.

We are aware that bibulous fibrous lining sheets have been "pasted", by applying paste with a brush or spray, before assembling them in the cell, and that such sheets have been used with paste-forming materials applied to the inner surface of the zinc cup, such surface carrying an oil or a saccharine solution adapted to cause the adherence of the paste-forming material. Such processes do not result in a paste layer having any marked moisture holding capacity, nor an effective degree of toughness. Our invention resides in the combination of at least one lining sheet of a fibrous bibulous material with a layer of

toughened paste capable of absorbing and retaining relatively large amounts of moisture. Various specific embodiments of this combination may be made within the scope 55 of the appended claims.

We claim:

1. Process of making dry cells, which comprises applying to a metal cup substantially non-interpenetrating contacting linings of toughened paste and of bibulous fibrous material, and placing a carbon electrode and conductive depolarizing mix within the cup so lined.

2. The invention according to claim 1, in which the paste lining is formed by applying paste to the surface of the metal, and toughening the paste thereon by application of heat.

3. Process of making dry cells, which comprises forming a layer of toughened paste upon the inner surface of a metal cup, placing a lining of bibulous fibrous material in said cup, inserting a carbon electrode in said cup, and tamping a conductive depolarizing mix into the space between the carbon electrode and sheet material.

4. A dry cell comprising a metal container electrode provided with substantially non-interpenetrating contacting linings of toughened paste and of bibulous fibrous material, a carbon electrode, and a conductive depolarizing composition in electrical connection with said cup and carbon electrode.

5. A dry cell comprising a metal container electrode having a layer of toughened paste upon its inner surface, a lining of bibulous fibrous material in said cup, a carbon electrode, and a conductive depolarizing composition in discrete particles filling the space between said electrode and sheet material.

6. In a dry cell of the type in which the depolarizing mix is tamped into a container electrode, means for insuring an adequate moisture content, comprising an absorbent layer of toughened paste between the mix and container electrode.

In testimony whereof, we affix our signatures.

RAYMOND C. BENNER.
HARRY F. FRENCH.
